Fig. 6.

FIG. 1 is a front elevation of a hemostat showing my new design, the same being shown in closed position;

FIG. 2 is a side elevation;

FIG. 3 is a top plan view;

FIG. 4 is a front elevation in open position;

FIG. 5 is a sectional view on an enlarged scale, taken along the line 5—5 of FIG. 1; and

FIG. 6 is a sectional view on an enlarged scale, taken along the line 6—6 of FIG. 1.

The rear elevations in the closed and open positions are identical to the front elevations shown in FIGS. 1 and 4.

The characteristic feature of my design resides in the specific configuration of the finger-engaging loops as best illustrated in FIGS. 1 and 4.

I claim:

The ornamental design for a hemostat, substantially as shown and described.
